US00D760624S

(12) **United States Design Patent**
Balaresque et al.

(10) **Patent No.:** US D760,624 S
(45) **Date of Patent:** ** Jul. 5, 2016

(54) **AUTONOMOUS DRONE**

(71) Applicant: **Lily Robotics, Inc.**, San Francisco, CA (US)

(72) Inventors: **Antoine Balaresque**, Atherton, CA (US); **Henry W. Bradlow**, Atherton, CA (US); **Robert N. Englin**, Los Angeles, CA (US)

(73) Assignee: **Lily Robotics, Inc.**, San Francisco, CA (US)

(**) Term: **14 Years**

(21) Appl. No.: **29/506,277**

(22) Filed: **Oct. 14, 2014**

(51) LOC (10) Cl. **12-07**

(52) U.S. Cl.

USPC **D12/16.1**

(58) **Field of Classification Search**

USPC D12/16.1, 19, 322, 323, 326, 327, 328, D12/329, 330, 339, 341, 342, 343, 344; D21/436, 438, 439, 440, 441, 446, 447, D21/448, 449, 450, 453

CPC B64C 39/00; B64C 30/00; B64C 29/00; B64C 5/06
